Primary Examiner—A. Hugo Word*Assistant Examiner*—I. Simmons*Attorney, Agent, or Firm*—Leydig, Voit & Mayer, Ltd.[57] **CLAIM**

The ornamental design for a trocar site stabilizer, as shown and described.

DESCRIPTION

- FIG. 1 is a front perspective view of the site stabilizer;
 FIG. 2 is a top plan view thereof;
 FIG. 3 is a bottom plan view thereof;
 FIG. 4 is a front elevational view thereof;
 FIG. 5 is a right side elevational view thereof;
 FIG. 6 is a rear elevational view thereof;
 FIG. 7 is a left side elevational view thereof;
 FIG. 8 is a perspective view thereof, the broken line showing of the trocar is for illustrative purposes only and forms no part of the claimed design;
 FIG. 9 is a top plan view of a second embodiment of A Trocar Site Stabilizer showing our new design; and,
 FIG. 10 is a front elevational view thereof.
